Inventor:

E. B. Weinrott,

by Merrill M. Blackburn.
Atty.

UNITED STATES PATENT OFFICE.

EMIL B. WEINROTT, OF MOLINE, ILLINOIS.

VENTILATED HEAD GARMENT.

Application filed October 24, 1924. Serial No. 745,639.

To all whom it may concern:

Be it known that I, EMIL B. WEINROTT, a citizen of the United States, residing at Moline, Ill., have invented certain new and useful Improvements in Ventilated Head Garments, of which the following is a specification.

My invention relates to improvements in ventilating means for garments worn upon the head and is illustrated more especially in connection with a ventilated cap. Among the objects of this invention are to improve upon means for ventilating head covering garments, to provide a novel cap having means for permitting free ventilation thereof and means for covering the ventilating means when desired; to provide a ventilated cap having a novel appearance both when the ventilating openings are covered and uncovered; and such further objects, advantages and capabilities as will later more fully appear.

My invention further resides in the combination, construction and arrangement of parts illustrated in the accompanying drawing and, while I have shown therein what I now consider the preferred embodiment of my invention I desire the same to be understood as illustrative only and not as limiting the said invention.

In the drawing annexed hereto and forming a part hereof, Fig. 1 is a perspective view of a cap embodying my invention; Fig. 2 is a fragmentary vertical section through the ventilator; Fig. 3 is a similar view showing the ventilating opening uncovered; Fig. 4 is a fragmentary elevation of my invention with the covering strap in position to permit ventilation; Fig. 5 is a perspective view of the covering strap; Fig. 6 is a perspective view similar to Fig. 5 but with a part of the strap broken away to show a modified construction upon the interior of the strap; and Fig. 7 is a view similar to Fig. 4, showing the strap in covering position.

Referring more in detail to the annexed drawing, the crown of the cap is designated by the numeral 1, the head encircling band by the numeral 2 and the visor by the numeral 3. The crown portion is shown as being made of a single piece of goods, but it is to be understood that this will usually be made of a plurality of sections stitched together at their edges, forming a cap such as is ordinarily referred to as a six quarter cap

or an eight quarter cap. This feature is unimportant and it is, therefore, not deemed necessary to show it.

As is customary in structures of this kind, the cap is provided with a lining 4 which is secured in any desired manner to the head band 2, the edge of the lining being customarily covered by a sweat band. Near opposite sides of the cap are provided ventilating openings in which are mounted open members or rings 5 which are preferably formed of metal. Each of these rings carries, in the preferred construction, a piece of material pervious to air, this material being designated by the numeral 6. It is at present believed that fine wire netting or gauze is preferable for this use. Both the outer portion 1 of the crown covering part of the cap and the lining 4 are perforated for the insertion of the open or ring members 5 and are secured together by these members when the latter are put in place. This construction provides means whereby air may enter the cap through the sides thereof into the space within the cap crown.

Spaced a little distance from the ring 5 are elongated openings provided with eyelets 7, which are preferably metallic and which form binding members for the edge of the goods where the latter is removed in making the openings. These elongated openings serve as means for permitting the straps 8 to slide into and out of the space between the crown portion and the lining, as shown in Figs. 2 and 3. The straps 8 are provided at their inner ends with crossbars 9 which limit the distance to which these straps may be pulled out of the cap, in drawing them down to cover the ventilating openings. Above and below each ventilating opening there is provided one member of a snap clasp. By preference, the male members 10 are applied to the body of the cap, while the female member 11, is applied to the strap. When it is desired to have the ventilating openings uncovered, the member 11 is unfastened from the lower member 10 and the strap is shoved up into the cap, the female member then being applied to the upper male member 10 as shown in Fig. 3. When it is desired to cover the ventilating openings, the operation is reversed, as shown in Fig. 2.

In Fig. 6 a thin resilient member 12 is shown between the two layers of the strap. This serves to stiffen the strap sufficiently

so that it can more easily be shoved into the cap, when uncovering the ventilating openings. This stiffening member is not regarded as essential but it is considered preferable to use it. It will be understood that the covering straps 8 are preferably of the same material as the crown portion, though a novel effect is produced by using a harmonizing color of a different weave of goods.

10 It will be understood that the specific disclosure herein may be departed from without departing from the spirit of my invention.

Having now described my invention, I 15 claim:

1. In a head garment, ventilating means comprising an open member extending through a wall of the garment and a cover member extending through an opening in 20 the garment and adapted to be so placed as to cover the opening in the open member or uncover the same.

2. A head garment having a crown portion provided with a ventilation opening 25 lateral with respect to the crown portion, another opening adjacent thereto, a covering strap extending through the last named opening and adapted to have the major portion shoved therethrough so that it will be concealed by the crown portion and to have said major portion pulled out so it may be made to cover the ventilation opening.

3. A head garment having a crown portion 35 provided with a ventilation opening lateral with respect to the crown portion, another opening adjacent thereto, a covering strap extending through the last named opening and adapted to have the major portion shoved therethrough so that it will be concealed by the crown portion and to have said major portion pulled out so it may be made to cover the ventilation opening, and means for securing the strap in either position.

4. A cap having a crown portion and a head band, said crown portion being provided with a ventilating opening extending from the exterior to the interior of the cap, 50 a binding ring mounted in said opening, said ring having an openwork material covering the opening of the ring, and a strap passing through the material of the crown to selectively cover or uncover the opening.

5. A cap having a crown portion and a head band, said crown portion being provided with a ventilating opening extending

from the exterior to the interior of the cap, 60 a binding ring mounted in said opening, said ring having an openwork material covering the opening of the ring, a second opening extending through the outer part of the crown portion, and a strap passing through the second opening for selectively covering or uncovering the first opening.

6. A cap having a crown portion and a head band, said crown portion being provided with a ventilating opening extending from the exterior to the interior of the cap, 70 a binding ring mounted in said opening, said ring having an openwork material covering the opening of the ring, a second opening extending through the outer part of the crown portion, a strap passing through the second opening for selectively covering or uncovering the first opening, and fastening means whereby the strap may be fastened in either of its positions of use.

7. A cap having a crown portion and a head band, said crown portion being provided with a ventilating opening extending from the exterior to the interior of the cap, a binding ring mounted in said opening, 75 said ring having an openwork material covering the opening of the ring, and a strap passing through the material of the crown to selectively cover or uncover the opening, said strap having a stiffening member whereby manipulation of the strap is 80 rendered easier.

8. A cap having a rounded opening and an adjacent elongated opening in the crown portion thereof, a covering strap extending through the elongated opening and adapted to be fastened in either of two positions, 95 selectively, and means whereby the strap may be fastened in either of such positions.

9. A cap comprising an outer portion and a lining, said cap having a rounded opening and an adjacent elongated opening in the crown portion thereof, the former extending through both the outer portion and the lining of the cap and the latter through the outer portion only, a covering strap extending through the elongated opening and adapted to be fastened in either of two positions, selectively, and means whereby the strap may be fastened in either of such positions, the strap, when pushed through the elongated opening, being located mainly between the lining and outer portions of the cap.

In witness whereof, I hereunto subscribe my name to this specification:

EMIL B. WEINROTT.
